UNITED STATES PATENT OFFICE.

CLARENCE R. VANDERPOOL, OF GRAND RAPIDS, MICHIGAN.

TRUSS PAD OR SUPPORT.

Application filed January 23, 1922. Serial No. 531,229.

To all whom it may concern:

Be it known that I, CLARENCE R. VANDERPOOL, a citizen of the United States, residing at Grand Rapids, county of Kent, State of Michigan, have invented certain new and useful Improvements in Truss Pads or Supports, of which the following is a specification.

This invention relates to improvements in truss pads or supports.

The objects of the invention are,

First, to provide an improved truss support which will hold a truss pad or an inguinal hernia with the minimum stress on the person of the wearer.

Second, to provide such a structure which will permit all ordinary movements of the body, such as stooping and sitting, without inconvenience and without relaxing the proper holding of the truss pad.

Further objects, and objects pertaining to details and economies of construction and operation will definitely appear from the detailed description to follow.

I accomplish the objects of my invention by the devices and means described in the following specification. The invention is clearly defined and pointed out in the claims.

A structure which is a preferred embodiment of my invention is fully illustrated in the accompanying drawing forming a part of this specification, in which:

Fig. I is a front view of my invention in position and in use, the figure of the wearer being merely indicated in outline and the back ring and strap portions and relation of the same being indicated by dotted lines.

Fig. II is a rear view of the truss supporting structure appearing in Fig. I, the relation of the belt only, at the front of the wearer being indicated by dotted lines.

Fig. III is a side view of the right hand side of the wearer of the structure appearing in Fig. I, showing the person of the wearer in stooping or partially sitting posture.

In the drawing similar numerals of reference refer to similar parts throughout the several views.

I will consider the various parts of my improved structure by their numerals of reference. 1 and 2 are belt parts connected by suitable loop to a back ring support 3 and provided with a belt buckle 4 between the ends thereof. 5 is the truss pad which is held from lateral displacement and up to

proper height by a pair of straps. Slide strap 6 is secured to the belt portion 2 at one side and connected by suitable pivot snap 7 to the truss pad. Adjusting buckle 8 is provided therefor. Side strap 9 is secured to the back ring at 10 and to the truss pad by the loop 11 and is adjusted by adjusting buckle 12. The back ring 10 is shown adjusted and substantially anchored opposite the hip bone and consequently in a position not subjected to material change by the bending of the body or the stooping as indicated in Fig. III. By use of the straps 6 and 9 it is very clear that the lateral position of the truss pad 5 can be exactly controlled and it can be adjusted to any required height desired. It is held down to place by the crotch strap 13 connected thereto by a pivot snap 14 and to the back ring 15 by a loop 16 and is adjusted by the buckle 17.

It will be observed that the belt parts 1 and 2, with their loop connections to the back ring, provide a very flexible belt effectively accommodating itself to the person of the wearer. The oblique adjusting strap secured to the belt cooperating with the oblique adjusting strap looped to the ring provide an equally effective means for adjusting the truss pad laterally and holding it up to its work. The crotch strap looped through the back ring and properly adjustable serves to hold the pad down to its work and prevents it moving out of engagement.

There will be observed to be a triple connection to the pad which is very flexible, indeed, and that the back ring with its flexible connection, being disposed substantially opposite, permits the complete hinging of all the parts without undue strain upon the person of the wearer, whether he is standing erect or is sitting or stooping.

Having thus described my invention what I claim as new and desire to secure by Letters Patent is:

1. In a truss support, the combination of a back ring, a pair of belt members with looped ends secured thereto with adjustable buckle therebetween, a truss pad, a side adjusting strap with suitable adjusting buckle stitched to one of said belt members with pivot connection to said pad, and a second side strap with adjustable buckle looped to the said back ring and loop-connected to said pad, a crotch strap with adjustable buckle connected by loop to the back ring and pivotally connected to said pad, where-

by the back ring with flexible connections is in opposed relation to the truss pad with its flexible connections, as specified.

2. In a truss support, the combination of a back ring, a pair of belt members with looped ends secured thereto with adjustable buckle therebetween, a truss pad, a side adjusting strap with suitable adjusting buckle stitched to one of said belt members with connection to said pad, and a second side strap with adjustable buckle looped to the said back ring and connected to said pad, a crotch strap with adjustable buckle connected by loop to the back ring and to said pad, whereby the back ring with flexible connections is in opposed relation to the truss pad, as specified.

3. In a truss support, the combination of a back ring, adjustable belt members loop-connected thereto, a truss pad, side adjust-

ing straps for the said truss pad, one of which is secured by loop to the said back ring and the other of which is secured to said belt, and an adjustable strap connected to said truss pad and looped to the said back ring, whereby the flexibly connected ring is opposed to the said truss pad.

4. In a truss support, the combination of a back ring adapted to be anchored over the region of and in proximity to the hip bone joint, adjustable belt members loop-connected thereto, a truss pad, and strap connections from said truss pad to said back ring.

In witness whereof, I have hereunto set my hand and seal in the presence of two witnesses.

CLARENCE R. VANDERPOOL. [L.S.]
